US0D1038120S

(12) **United States Design Patent** (10) **Patent No.:** **US D1,038,120 S**
(45) **Date of Patent:** **** Aug. 6, 2024**

(54) **WIRELESS TRANSMITTER**

(71) Applicant: **Shenzhen Zeus Electronic Technology Co., Ltd**, Shenzhen (CN)

(72) Inventor: **Qingxiang Zheng**, Shenzhen (CN)

(**) Term: **15 Years**

(21) Appl. No.: **29/835,722**

(22) Filed: **Apr. 21, 2022**

(51) **LOC (14) Cl.** **14-02**

(52) **U.S. Cl.**

USPC **D14/358**

(57) **CLAIM**

The ornamental design for a wireless transmitter, as shown and described.

DESCRIPTION

FIG. 1 is a perspective view of a wireless transmitter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the wireless transmitter; and,

FIG. 10 is another exploded perspective view of the wireless transmitter.

The broken lines in the drawings depict portions of the wireless transmitter that form no part of the claimed design.

1 Claim, 10 Drawing Sheets
